His attorney

UNITED STATES PATENT OFFICE.

GEORG SPIESS, OF LEIPZIG-REUDNITZ, GERMANY.

SHEET-FEEDING DEVICE.

Application filed June 5, 1922. Serial No. 565,902.

To all whom it may concern:

Be it known that I, GEORG SPIESS, a citizen of the German Republic, residing at Leipzig-Reudnitz, Germany, have invented 5 certain new and useful Improvements in Sheet-Feeding Devices, (for which I have filed an application in Germany on the 9th of June, 1921), of which the following is a specification.

10 There have already become known conveying tables for mechanical sheet feeders which are oscillable around a shaft of the stationary drive for the devices arranged upon the table without requiring the loosening 15 of the connection before the oscillating movement takes place. With this object in view the devices arranged upon the table are driven from a shaft mounted at the long side of the table and connected by a 20 pair of cog wheels with the stationary driving axle which serves as pivot pin. This problem is not solved by this known device in a satisfactory manner as at the oscillation of the table the shaft at the long side 25 of the table must execute a part revolution as its cog wheel rolls upon the cog wheel of the stationary shaft. This part revolution of the intermediary shaft causes a movement of all the devices on the table 30 which are connected with this shaft so that the oscillating of the table is much impeded by the resistance offered by these devices, so that it can be carried out in a limited measure only. The conveying tables of 35 known construction present further the inconvenience that the system of driving rods and levers for the device arranged at the other side of the table, for instance the drawing mark, must extend over the entire 40 breadth of the table whereby the work to be done upon the table is rendered very difficult to execute.

According to this invention these inconveniences are avoided by operating the 45 working tools mounted upon the table, directly from stationary driving elements through the intermediary of levers and by constructing the stationary driving device in such a manner that the link which connects the end member of the same with the working device arranged upon the table is situated in or approximately in the axis of

oscillation of the table. This construction can be used for the driving elements for any of the devices mounted on the table. 55

A form of construction of a conveying table is shown by way of example on the accompanying drawing in which, in order to make the drawing clearer only the driving elements for two working devices are 60 shown which are mounted upon the table.

Fig. 1 shows in side elevation the front end of a sheet feeder with a conveying table in the working position.

Fig. 2 is a similar view, the table being 65 shown in the lifted position.

1 is the frame of the sheet feeder with the fixed pile table 2 and the conveying table 4 for the mechanical feeding which is adapted to oscillate about shaft 3. In the 70 frame of the sheet feeder a grooved cam disk 5 is mounted which is designed to operate the registering mark arranged at the front end of the conveying table. This registering mark serves to regulate the position of the sheet before the same is inserted into the machine. The rods for transmitting the drive from disk 5 to the registering mark consist of a two-armed lever 7 fulcrumed at 6 which is connected by a rod 80 75 with a two-armed lever 10 fulcrumed at 8. This lever 10 is connected by a rod 11 with a lever 12 hingedly mounted upon table 4 and designed to transmit its movement to the registering mark by means of 85 other connecting elements not shown on the drawing. The two-armed lever 10 is so arranged that, at a determined position of this lever, the pivot axle 3 of the table 4 coincides exactly or approximately with the 90 pivot bolt 13 which connects the lever 10 with connecting rod 11. At the front end of the conveying table a device is further arranged which is designed to automatically stop the machine if the sheet is not 95 placed exactly against the front marks or if the conveying does not work correctly.

It comprises a two-armed lever 14 keyed upon the axle of an oscillating lever 15 and which is connected by a connecting rod 16 100 with one of the arms of an angle lever 17 which is hingedly mounted at 18 upon the frame of the sheet feeder and connected by connecting rod 19 with the device for the

throwing out of gear of the machine. The angle lever 17 is so arranged that its pivot bolt 20 which connects its upper arm with the connecting rod 16, is oscillated by an oscillating axle of the conveying table and that the amplitudes to either side are almost equal, so that, if lever 17 is at the middle position at the lifting of the table, the rods are not operated.

10 The amplitude of the oscillation varies according to the type of the machine. With machines having a greater amplitude of oscillation if the conveying table would be lifted for instance at the extreme position of the lever 17 or 10, a movement will be produced in the rods which could lead to disturbances in or to rupture of parts of the machine. This is prevented by a safety device which permits the oscillation of the conveying table only at the normal position of all the elements for the transmission of movement, for instance if the pivot pins which connect the connecting rods of the devices mounted upon the table with the rod-levers 25 pivoted at fixed points, are exactly or approximately at the middle of the path of oscillation which means that they coincide with the pivot axle 3 of the table. With small tables, which are to be lifted by hand, locking means are provided which permit the lifting only if the locking of the table has been released by the normal position of the rods. With large tables a lifting device is used which remains locked as long as the rods have not yet adopted the normal position. Such a locking device is shown on the drawing.

40 The locking and unlocking is controlled in such a manner that at the unlocking of the winch all the rods are at the normal position. The lever 7 is best adapted for this purpose. It is connected with an angle lever 22 by a rod 21, said angle lever being connected by a rod 23 with a locking arm 24. 45 This locking arm 24 engages with its nose in a ratchet wheel 25 mounted upon the shaft of the crank handle of the winch. If the lower arm of lever 7 is in the extreme left hand side position the locking nose of lever 20 is disengaged from the teeth of the

ratchet wheel and the conveying table can be swung up.

I claim:-

1. An improved oscillable conveying table for the mechanical feeding of sheets in printing machines, folding machines and similar machines comprising in combination with the conveying table and with the working devices mounted upon the same, a driving shaft, stationary rods for transmitting the movement from said driving shaft to the said working devices, operating rods of said working devices, links connecting said stationary rods with said movable rods, pivot bolts for said links, the links being arranged so that their pivot bolts are situated in or approximately in the pivoting axis of the conveying table so that said table can be lifted without the prior lowering of the connection between the working devices mounted upon the same and the driving rods fixed to the stationary parts of the machine. 60

2. An improved oscillable conveying table for the mechanical feeding of sheets in printing machines, folding machines and similar machines comprising in combination with the conveying table and with the working devices mounted upon the same, a driving shaft, stationary rods for transmitting the movement from said driving shaft to the said working devices, operating rods of said working devices, links connecting said stationary rods with said movable rods, pivot bolts for said links, the link being arranged so that their pivot bolts are situated in or approximately in the pivoting axis of the conveying table so that said table can be lifted without the prior lowering of the connection between the working devices mounted upon the same and the driving rods fixed to the stationary parts of the machine. 70

75 In testimony whereof I affix my signature in presence of two witnesses.

GEORG SPIESS.
